UNITED STATES PATENT OFFICE.

CORNELIUS VAN ZYL, OF SHELDON, IOWA.

MACHINE FOR STAPLING CHICK BOXES.

Application filed November 2, 1926. Serial No. 145,842.

This invention relates to stapling machines and particularly to machines for forcing relatively wide staples through boxes used for containing or transporting chicks.

5 The general object of the invention is to provide a machine of this character which is very simple, may be easily mounted, and which has been found to be thoroughly effective in practice and whereby a staple 10 may be forced through the pasteboard of the box and the outer ends of the staple overturned upon the flap of the box.

My invention is illustrated in the accompanying drawings wherein:—

15 Figure 1 is a side elevation of a stapling machine constructed in accordance with my invention;

Fig. 2 is a fragmentary vertical sectional view;

20 Fig. 3 is a face view of the upper end of the plunger;

Fig. 4 is a fragmentary top plan view of the forward end of the upper jaw;

25 Fig. 5 is a section on the line 5—5 of Figure 2.

Referring to these drawings the support for the stapling machine consists of a plank or equivalent member designated 10, which is preferably of hard wood and which may 30 be fastened against the wall of a house, a post, or any other structure. Attached to the face of this plank 10 is a plate 11 of metal which is attached by means of bolts or screws 12 and which has a slot 13 formed in its face. Extending from the plate 11 is a vertically movable arm 14, the inner end 35 of which is curved, as at 15, for insertion within the slot 13, the plank 10 being recessed immediately behind the slot to accommodate this curved portion. A cotter pin or like stop 16 is disposed through the inner end of the arm 14 so as to prevent it 40 from being forced into the slot 13 to too great an extent.

45 Welded or otherwise attached to the face of the metal plate 11 is an outwardly and downwardly extending bracket 17. The lower end of this bracket is outwardly extended in a horizontal plane and then 50 formed with an upward extension 18 having guides 19 for a vertical plunger 20. The upper end of this plunger 20 is formed with a slot for the reception of the end of the arm 14.

55 Welded or otherwise attached to the face of the plate 11 is the angular end 21 of an

upper jaw 22. This jaw extends horizontally outward and the extremity of the jaw is provided on its under face with the steel block 23. This block and the extremity of 60 the plate which forms the jaw 22 is notched as at 24, so as to permit the passage of the plunger 20. This notch or slot 24 serves as a guide for the staple and prevents it from buckling when it is forced through the box 65 by the plunger 20. The upper jaw 22 is also welded or otherwise rigidly connected to the brace or bracket 17.

Hingedly mounted upon the plate 11 below the upper jaw is the lower jaw 25 which 70 extends out beneath the notch or slot 24 in the upper jaw. A bolt which constitutes a stop and is designated 26 passes downward through the upper jaw and through the lower jaw. This bolt is held to the upper 75 jaw by two nuts 27 and at its lower end carries a head or nut 28. A spring 29 is disposed between the upper jaw and the lower jaw which forces the lower jaw downward when the machine is not in use. The outer 80 end of the lower jaw constitutes an anvil formed with a concavity immediately below the slot 24 for the purpose of bending or overturning the points of the staple and clinching them.

85 Resting upon the head or nut 28 is a lever 30 which at its outer end is provided with a small block 31 and at its inner end has an aperture for the passage of the pull rod 32. This rod extends downward through guides 33 and has its lower end connected by a coiled compression spring 34 to a treadle 35. This treadle is hingedly connected to the plank or post 10 in any suitable manner and obviously when the treadle is depressed, the 90 tension on the spring 34 will be increased. This spring normally acts to force the outer end of the lever 30 upward against the jaw 25 so as to hold the outer end of this jaw 95 snugly up against the box which is being 100 stapled.

Engaging over the arm 14 is a yoke 36 having outwardly turned ends and passing through these outwardly turned ends of the yoke are the two rods 37 which extend downward and are operatively connected with the treadle 35. A spring 38 is connected to the plank 10 to the arm 14 and acts to lift the arm. Attached to the block 23 of the upper jaw 22 is an outwardly and upwardly inclined staple guide 39 which extends downward and toward the jaw, the lower end of

this staple guide being formed with a hinged leaf 40 which when opened, permits the removal of a staple which may have become turned within the machine or which is bent or deformed.

The operation of this mechanism is as follows:—When the foot treadle 35 is released, the tension of spring 34 is entirely relieved and the rod 32 will, of course, be moved upward by the action of lever 30. This is due to the fact that the spring 29 forces downward upon the hinged jaw 25, thus releasing the outer end of the lever 30 downward and drawing upward on the inner end of the lever 30 and the rod 32. While the stapler will work without this spring 29, I find that the stapler acts quicker and much more surely with the spring 29 than without. In stapling the box, the folded corner of the box is placed over the upper face of the jaw 25 and the treadle 35 is forced downward, which places the spring 34 under tension, which causes the lever 30 to force the lower jaw up against the upper jaw. The rods 37 pass loosely through the ends of the yoke so that an initial movement of the treadle 35 may be made before the stops 37^a on the rods engage the yoke. When so engaged, the downward movement of the treadle forces the arm 14 downward, and this forces the plunger 20 downward. A staple has been previously placed within the staple guide. It comes to rest with its head immediately below the plunger so that upon a complete depression of the treadle, the plunger will force the staple through the box and the ends of the staple, striking the concave face of the lower jaw, will be turned inward or clinched in an obvious manner. A release of pressure upon the treadle immediately causes the lifting of the plunger and then the release of the box.

This device is extremely effective in stapling chick boxes which require a wide staple. It takes up very little room, and may be easily supported in a convenient position.

This machine is particularly desirable for overturning wide staples upon pasteboard chick boxes and one of the advantages of this device is that it permits staples to be used which are much wider than those commonly used in building chick boxes. These chick boxes are made of paper or cardboard and come to the user in a flat or knocked down condition. The sides and the ends are folded upward and the ends of the end pieces are folded around the corners of the box and stapled together and by the use of very wide staples, the pasteboard or paper is held much more securely and firmly and without danger of being torn apart.

It will be obvious that while I have illustrated certain details of construction and arrangement of parts which I have found to

be particularly effective in practice, many changes might be made in these details without departing from the spirit of the invention as defined in the appended claims.

I claim:—

1. A stapling machine of the character described including a support, an upper jaw rigidly mounted upon the support and extending out therefrom and having a staple receiving recess at its outer end, a bracket mounted upon the support and engaging said jaw and provided with guides immediately above the recess, a plunger operating through said guides and recess, an arm mounted upon the support for vertical movement and connected to the plunger, a treadle mounted upon the support and operatively connected to the arm, a lower jaw hingedly mounted upon the support and having an upsetting anvil disposed below said recess, a lever supported below the lower jaw and having one end bearing against the same, and a connection between the other end of the lever and said treadle including a coiled contractile spring. 90

2. A stapling machine including a support, an upper jaw rigidly mounted upon the support and recessed at its end to receive a staple, a staple guide secured thereto, plunger guides mounted upon the support, a plunger operating through said guides and through the recessed end of the jaw, an arm swingingly connected to the support and at its outer end engaging the plunger, a treadle mounted upon the support, a yoke extending over the arm, rods extending upward from the treadle and having sliding engagement with the yoke and carrying stops at their upper ends, a lower jaw hingedly connected to the support and at its outer end having an upsetting anvil disposed below the recessed end of the upper jaw, a supporting pin passing through the upper jaw and lower jaw and having a stop on its lower end, a lever mounted upon said stop as a fulcrum and having its outer end engaging with the lower jaw, and a connection between the treadle and said lever and including a coiled contractile spring. 105

3. A stapling machine including a support having a recess, a rigid upper jaw mounted upon the support, a staple guide associated therewith, a plunger mounted for movement through the recess in the upper jaw, a lower jaw hingedly supported upon said support, an arm having a curved inner end having rocking engagement in said recess and operatively connected to the plunger, a treadle operatively connected to the arm, and means acting upon a downward movement of the treadle to move the lower jaw upward against the upper jaw and upon a release of the treadle to cause the lower jaw to move downward away from the upper jaw. 130

4. A stapling machine including a support, a rigid upper jaw mounted upon the support and having a recessed outer end, a staple guide associated therewith, a plunger mounted for movement through the recess in the upper jaw, a lower jaw hingedly mounted upon said support, a lever pivotally supported at its middle and engaged at its outer end with said lower jaw, a treadle, a connecting rod extending between the treadle and the inner end of said lever whereby a depression of the treadle will cause the movement of the lower jaw, and means operatively connecting the treadle to the plunger.

5. A stapling machine including a support, a rigid upper jaw mounted upon the support and having a recessed outer end, a staple guide associated therewith, a plunger

mounted for movement through the recess in the upper jaw, a lower jaw hingedly mounted upon said support, a lever pivotally supported at its middle and engaged at its outer end with said lower jaw, a treadle, a connecting rod extending between the treadle and the inner end of said lever whereby a depression of the treadle will cause the movement of the lower jaw, and means operatively connecting the treadle to the plunger, said means positively engaging with the plunger to secure a downward movement thereof after the treadle has been moved to an extent sufficient to raise the lower jaw into operative relation to the upper jaw.

In testimony whereof I hereunto affix my signature.

CORNELIUS VAN ZYL.
